United States Patent Office.

ABRAHAM H. CARPENTER, OF NEWARK, NEW JERSEY.

Design No. 4,056, dated May 24, 1870.

DESIGN FOR AN OXYGEN-GENERATOR.

The Schedule referred to in these Letters Patent and making part of the same

To all whom it may concern:

Be it known that I, ABRAHAM H. CARPENTER, M. D., of Newark, in the county of Essex and State of New Jersey, have invented a new and original Design for Oxygen-Generator; and I do hereby declare that the following is a full, clear, and exact description thereof, which will enable others skilled in the art to make and use the same, reference being had to the accompanying drawing forming part of this specification.

This invention relates to a new design for an oxygen-generator, which is to be applied to family use, and which is therefore of convenient size and of such shape that it can be readily used for producing small quantities of gas.

The generator consists of the retort A, cap B, and L-shaped pipe C.

The retort rests upon three, more or less, legs D D, which hold it in an upright position, and high enough above the top of a table or other article to admit a lamp underneath. The retort is of cylindrical form.

The cap is also cylindrical, as shown, and is fitted upon and projects from the neck a of the retort.

The pipe C has a perforated section, b, at its outer end, which section is somewhat larger than the body of the pipe.

I claim as my invention—

The design for an oxygen-generator, as shown.

A. H. CARPENTER, M. D.
